UNITED STATES PATENT OFFICE.

EMIL L. JOHNSON AND OLOF LUNDSTEN, OF ATTLEBORO, MASSACHUSETTS.

BUCKLE.

Application filed November 12, 1920. Serial No. 423,558.

To all whom it may concern:

Be it known that we, EMIL L. JOHNSON and OLOF LUNDSTEN, citizens of the United States, residing at Attleboro, in the county 5 of Bristol and State of Massachusetts, have invented certain new and useful Improvements in Buckles, of which the following is a specification.

This invention relates to buckles for holding a belt in adjusted position about the body of the wearer, and the object of this invention is to provide an improved buckle of this character wherein the clamping member is formed complete from a single 15 plate of sheet metal, and is provided with a cam-shaped gripping portion formed by rolling inward one edge of this plate, the same being also provided with pivot lugs which are pivotally mounted in ears in the 20 side walls of the buckle body.

The invention further consists in the folding of the metal of which the pivot ears are constructed so as to form doubly thick bearings in which the clamping member is 25 mounted.

The nature and advantages of the invention will be better understood when the following detail description is taken in connection with the accompanying drawings, the 30 invention residing in the combination and arrangement of parts as claimed.

In the drawings forming part of this specification, like numerals of reference indicate similar parts in the several views and 35 wherein:—

Figure 1 is a sectional side elevation of our improved buckle, showing our improved form of clamping member as binding a belt end against the inner surface of the buckle 40 body.

Figure 2 is an end elevation sectioned on line 2—2 of Figure 1 through the buckle body and jointed ears, and showing the clamping member pivotally mounted therein.

Figure 3 is the same as Figure 2 but with the clamping member removed, illustrating the inwardly folded portions of the pivot ears as forming doubly thick pivot bearings.

Figure 4 is a perspective view of the cam-shaped clamping member.

Figure 5 is a perspective view of the inner side of the buckle body.

With reference to the drawings 10 des-

ignates the buckle body which is preferably 55 formed of sheet metal and provided at each edge with inwardly turned side walls 11.

At one end of the buckle body we have formed integral pivot ears 12 each of which is preferably formed with an integral extension portion 13 on its outer edge, which is folded inwardly to provide pivot ear walls of a double thickness. These inwardly folded portions are pierced as at 14 and the outer wall is preferably forced or 60 swaged outwardly as at 15 providing a recess to receive and cover the end of the clamp pivot. By this construction the ear is greatly stiffened and at the same time it also effectually prevents the clamping member from being disengaged from its pivot eyes even when subjected to the most severe strains. Then again by not piercing the outer wall of the pivot ear when gold plated stock is used only the plated portion is exposed as 65 it serves to cover the bearing portion as well as the base metal pivot ends of the clamping member.

Another feature of this invention is the unique and practical construction of the 80 clamping lever 16 which is preferably formed of sheet metal, one edge of which is pierced as at 17 to permit the belt end 18 to be secured thereto while the opposite end of this clamping member is rolled or curled 85 under or beneath the main body thereof as at 19, see Figure 4, the stock of the lever being of such thickness so that when so rolled or curled it is sufficiently stiff to grip and bind a belt against the inner body of the 90 buckle and effectually prevent the same from slipping.

On the edges of this clamping plate are formed integral pivoting lugs 20 which when mounted in the eyes 14 of the pivot ears cause the rolled portion of the clamping plate to have a cam action whereby the pull or strain of the belt end 18 on the clamp lever 17 causes the inner edge 21 of this cam to grip the opposite end 22 of the belt and bind the same against the inner surface of the body portion of the buckle.

By this construction it will be seen that the buckle is constructed of but two parts that is the body and the clamping member, the joint ears of the body being reinforced by folding the stock inwardly while the clamping member is formed strong and

rigid and of one piece, providing a cam-shaped clamp bar by simply rolling inwardly one edge thereof.

In some instances it is found desirable to 5 form the body portion of the buckle crowning, and in order to cause the clamping member to grip the belt properly against the concaved inner face thereof the cam or gripping portion of this clamp member is 10 also formed correspondingly oval or rounding throughout its length so as to fit the crowning portion of the buckle body and bind the belt securely therein.

The buckle is extremely simple and practical in construction and effective in its 15 operation.

The foregoing description is directed solely towards the construction illustrated, but we desire it to be understood that we 20 reserve the privilege of resorting to all the mechanical changes to which the device is

susceptible, the invention being defined and limited only by the terms of the appended claim.

We claim:

A buckle comprising in combination a clamping member formed of a sheet-metal plate with one edge rolled under into tubular form providing an integral clamping edge, said plate being provided with integral laterally-extending pivot lugs and a body member having portions of its side walls folded inwardly forming stock of a thickness double that of the body and said lugs bearing in both the inward fold and also 30 the body member providing a pivotal mounting in said double side walls.

In testimony whereof we affix our signatures.

EMIL L. JOHNSON.
OLOF LUNDSTEN.
